FRANK I. KIMBALL, OF WEST HAVEN, CONNECTICUT, ASSIGNOR TO SARGENT & COMPANY, OF NEW HAVEN, CONNECTICUT, A CORPORATION OF CONNECTICUT.

PADLOCK.

1,128,004.

Specification of Letters Patent.

Patented Feb. 9, 1915.

Application filed August 29, 1914. Serial No. 859,220.

To all whom it may concern:

Be it known that I, FRANK I. KIMBALL, a citizen of the United States, residing in West Haven, in the county of New Haven 5 and State of Connecticut, have invented certain new and useful Improvements in Padlocks, of which the following is a full, clear, and exact description.

This invention relates to padlocks, and 10 more particularly to pin tumbler padlocks. Moreover, it refers especially to pin tumbler padlocks of the sliding shackle type, although in some cases a swinging shackle may be employed.

One of the objects of the invention is to 15 provide a pin tumbler padlock wherein the body or case may be constituted by a single piece or block of metal such as produced, for example, by a process of extrusion, and 20 in which the pin tumblers are so located and housed as to prevent very effectively the picking of the padlock by attacking the tumblers from the exterior of the case. Heretofore it has been a common practice 25 to locate the tumblers on the same side of the case as the plug or plugs that fill up the drill holes, which construction is open to the disadvantage that access to the tumblers may be readily had if the plug or plugs are 30 removed. According to my invention, however, the pin tumblers are located on the opposite side of the case with reference to the cover for the drill holes, with a resulting increase in the security of the padlock.

Another object of the invention is to 35 provide a padlock wherein the tumbler pins or sections adapted to engage sockets in the body of the case may be inserted readily from the bore for the key plug in assembling 40 the padlock, just as in assembling the ordinary cylinder lock, instead of introducing said tumbler pins from the outside of the case, which has been customary heretofore in certain pin tumbler padlocks. This facilitates manufacture and permits the pin 45 tumblers to be located on the opposite side of the case with reference to the drill hole plugs, as above stated.

The invention also contemplates the protection 50 vision of a padlock wherein a plug which is adapted to fill the opening for the loading tool serves another and very useful function, to wit, that of carrying or mounting the bolt which is actuated by the key plug

to engage and disengage the shackle. This 55 simplifies the construction, and also facilitates assembling.

To these and other ends the invention consists in the novel features and combinations of parts to be hereinafter described and 60 claimed.

In the accompanying drawings, Figure 1 is a front elevation of a sliding shackle padlock embodying my improvements, with the shackle closed. Fig. 2 is a vertical longitudinal section of the padlock in the position shown in Fig. 1. Fig. 2^A is a section on line 2^A—2^A of Fig. 2. Fig. 3 is a similar section with the shackle open. Fig. 4 is a longitudinal section through the body or case, with 70 the other parts removed, and Figs. 5 and 6 are details of the bolt and the bolt carrying plug.

The body or case 10 of the padlock may 75 be constituted by a single piece or block of metal, provided with suitable bores or drill holes for the shackle 11, the key plug 12, and the pin tumblers 13. In the form shown the shackle 11 is a sliding shackle having a long end 11^a operating in a long bore 14 at 80 one side of the case, and having a short end 11^b operating in a short bore 15 at the opposite side of the case. In the bore 14 is the usual spring 16 for protracting or opening the shackle when the same is released by the 85 key mechanism. It will be observed from Fig. 4 that the sockets 17 for those sections of the pin tumblers which engage the body of the case and for the tumbler springs 18 are located beneath the short shackle bore 90 15 at the same side of the case. These sockets 17 are formed by drilling holes laterally through the body 10 from the opposite side, that is, from the side having the long shackle bore 14. The drill holes in the outside wall of the case, designated at 19, are at the same side of the case as the long shackle bore 14 and are subsequently covered or 95 filled up by any suitable closure means such as the small plugs 20.

The key plug or barrel 12 is accommodated in a bore 21, open, as usual, at the bottom of the case, as shown in Fig. 2. Moreover, in accordance with my improvements the bore 21 is open completely through the 105 case to present an opening at the top of the case as well as at the bottom. In the form shown the opening at the upper portion of

the case (Fig. 4) is of a slightly larger diameter than the major portion of the key plug bore 21, as indicated at 22. In the wall between the opening 22 and the bore 15 is an aperture 23, adapted to be engaged by a bolt 24, actuated by a spring 25 to engage the notch 26 in the free end of the shackle. The bolt 24 is disengaged from the shackle by rotation of the key plug 12, which has an eccentric shoulder or projection 27, adapted to engage a shoulder 28 on the bolt. This movement of the bolt by the key plug is more or less customary, and need not be described in further detail.

15 The bolt 24, which may vary considerably in form without departing from my invention, is located in the open portion 22 and is carried by a part adapted to close or fill said open portion 22 at the top so as to close 20 the padlock body at that point. In the form illustrated the closure member for the upper end of the key plug bore, that is, for the extension of said key plug bore, is in the form of a plug 29. The bolt 24 is carried by 25 the plug 29. In the padlock selected for illustration the bolt 24 is of the sliding type, and is adapted to slide in an opening or bore 30 in the plug 29. The bolt 24 is adapted to be confined within the lines of 30 the plug 29, so that both of them may be assembled in the padlock as a unit. In doing this the normally projecting end of the bolt, and the spring 25, are confined within the lines of the plug, and the latter is introduced 35 into the open portion 22 from above. When the plug 29 is finally seated in its socket the bolt 23 projects through the opening 23 and is adapted to engage the free end of the shackle. The spring 25 abuts at one end a 40 part of the bolt and at the other end it reacts against a wall 31 separating the bore 22 from the bore 14. The plug 29 is held permanently in position by a pin 32, passing through the body 10 and through an opening 33 in the plug 29. Dislocation of the key plug relative to the body of the case is prevented by a similar pin 34, and dislocation of the shackle is prevented by a pin 35 45 coöperating with the longer arm 11^a of the shackle.

50 In assembling the various parts of the padlock the procedure is substantially as follows: The drill holes 19 may be filled up at any time after the pin tumbler sockets 17 have been formed in the case. The pin tumblers are inserted in substantially the same manner which is customary in ordinary cylinder locks. A loading tool is pushed 55 into the bore 21 from the top through the open portion 22, and the tumbler springs 18 and certain of the tumbler pins or sections are inserted laterally into the sockets 17 from the bore 21. The key plug 12 is introduced into the axial bore in the case from 60 the opposite end, carrying other tumbler

sections, and as the loading tool is moved upward in the bore and out of the top of the bore the key plug is similarly moved upward so as to maintain contact therewith until the tumbler sections carried by the key plug are 70 brought into coöperation with the corresponding tumbler sections of the case. The plug 29, with the bolt 24, is inserted in the opening 22 after the loading tool has been withdrawn, the shackle is placed in position, 75 the pins 34, 35 and 32 are driven through the case to lock the key plug, shackle and bolt plug in place, and the protruding ends of said pins are then polished off in the usual manner.

80 The operation of the device will be obvious, for the most part, from the foregoing description. In the locked position, shown in Fig. 2, the spring 25 maintains the locking bolt in locking engagement with the 85 shackle. When a key 36 is introduced into the key plug to rack the tumblers the key plug is released, and in turning its projection or shoulder 27 will engage the shoulder 28 on the bolt and withdraw the latter from 90 engagement with the shackle, thereby permitting the shackle to be shot outward by its spring 16, as shown in Fig. 3. When the shackle is pushed inward again the bolt automatically reengages its notch 26. When 95 the padlock is locked the tumblers cannot be picked by way of the drill holes 19, even if the plugs 20 or their equivalent are removed, because the longer arm 11^a of the shackle effectively blocks said drill holes, and in any case, picking is made very difficult owing to the fact that the tumbler sockets in the case are at the other side of the key plug. Direct attack on the bolt by means of a wire or other instrument passed longitudinally 100 through the key-way is prevented by a plate or blocking portion 37 located beneath the bolt in line with the key-way. In the form shown this blocking portion or plate 37 is carried by the key plug in such a manner as 105 to lie within the opening 38 in the bottom of the plug 29 and fill up substantially all the space in said opening 38 not occupied by the bolt operating projection 27. Thus, a wire inserted into the key-way will abut 110 against the plate 37 and will be unable to contact with and withdraw the bolt.

115 Various modifications in the details of the construction may be adopted within the scope of the invention as defined in the 120 claims.

What I claim is:

1. In a padlock, a case formed of a single block of metal having a key plug bore, tumbler sockets at one side of the bore and drill holes at the opposite side of the bore, a key plug in said bore, pin tumblers coöperating therewith, a closure for said drill holes substantially within the lines of the case, and a shackle extending into openings of said case 125 130

on opposite sides of the key plug and controlled by the latter; substantially as described.

2. In a padlock, the combination of a case 5 formed of a single block of metal having a key plug bore, tumbler sockets at one side of the bore and drill holes at the opposite side of the bore in line with the tumbler sockets, means substantially within the lines of the 10 case to close said drill holes, a shackle engaging openings in the case at opposite sides of the key plug, and a shackle controlling bolt within the lines of the case operatively connected with the said key plug; substantially as described.

3. In a padlock, a case formed of a single block of metal, having a central key plug bore, shackle bores parallel to said key plug bore, and on opposite sides thereof, lateral 20 pin tumbler sockets leading from the bore on one side, there being drill holes in line with said sockets at the opposite side of the case, means for closing said drill holes, a key plug in said first named bore, pin tumblers engaging the sockets of the case on the opposite side thereof with reference to said drill holes, a sliding shackle engaging the shackle bores, and a shackle controlling bolt operatively connected with said key plug; substantially 25 as described.

4. In a padlock, a case formed of a single block of metal having a central key plug bore extending completely therethrough, shackle bores parallel with said key plug bore, at opposite sides thereof, a sliding shackle engaging said shackle bores, a key plug closing one end of said key plug bore, and operatively connected with said shackle, pin tumblers coöperating with said key 40 plug, and means for closing the other end of the key plug bore; substantially as described.

5. In a padlock, the combination of a case having a key plug bore extending completely therethrough, a shackle adapted to engage openings in said case at opposite sides of said key plug bore, a key plug closing one end of said key plug bore, a bolt for locking the shackle, operatively connected 50 with said key plug, adjacent the other end of the key plug bore, and means for closing such other end of the key plug bore; substantially as described.

6. In a padlock, the combination of a case 55 having a key plug bore extending completely therethrough, a shackle adapted to engage openings in said case at opposite sides of said key plug bore, a key plug closing one end of said key plug bore, a bolt for locking the shackle, operatively connected with said key plug, adjacent the other end of the key plug bore, and means for closing such other end of the key plug bore, comprising a plug which serves as a bolt carrier; substantially as described.

7. In a padlock, the combination of a case having a central key plug bore extending completely therethrough, a shackle adapted to engage openings in the case at opposite sides of said key plug bore, a key plug in 70 said bore, and closing one end thereof, pin tumblers coöperating with said key plug, a sliding bolt for locking the shackle, operatively connected with said key plug, and a member for closing the other end of the key 75 plug bore and for guiding the bolt; substantially as described.

8. In a padlock, the combination of a case having a key plug bore extending completely therethrough; a shackle attached to 80 the case, a key plug set in said bore from one end, and a shackle controlling bolt set in said bore from the other end; substantially as described.

9. In a padlock, the combination of a case 85 constituted by a single block of metal, said case having a key plug bore extending completely therethrough, and being provided with pin tumbler sockets on one side of the bore and drill holes on the opposite side of 90 the bore, a key plug closing one end of said key plug bore, pin tumblers in said sockets, coöperating with said key plug, means for closing said drill holes, a shackle, a shackle controlling bolt operatively connected with 95 said key plug, and means for closing the open end of the key plug bore; substantially as described.

10. In a padlock, a case having a key plug bore extending completely therethrough, a 100 shackle attached to said case, a key plug set in said key plug bore from one end, a shackle controlling bolt set in said key plug bore from the other end, and means interposed between the key plug and the bolt for preventing the withdrawal of the latter by a 105 picking tool; substantially as described.

11. In a padlock, the combination of a case having two shackle openings at one end and provided with a third opening at the 110 same end of the case intermediate said shackle openings, a shackle adapted to engage said shackle openings, a bolt located in said third opening, means for operating said bolt, and a filler plug for said third opening; substantially as described.

12. A padlock having an opening extending completely therethrough, a key plug closing said opening at one end, a plug closing said opening at the opposite end, a bolt 120 inclosed in the case by said last named plug, and a shackle controlled by said bolt; substantially as described.

13. A padlock having a case with an opening extending completely therethrough, a 125 key plug closing said opening at one end, a member closing said opening at the other end, pin tumbler mechanism coöperating with said key plug, and a shackle controlling bolt guided by said closing member and 130

operatively connected with the key plug; substantially as described.

14. A padlock having a case with an opening extending completely therethrough, a key plug closing said opening at one end, a pin tumbler mechanism coöperating with said key plug, a member closing said opening at the opposite end, a shackle, and a sliding shackle controlling bolt mounted in and guided by said closing member; substantially as described.

15. In a padlock, the combination of a case having two shackle openings at one end and provided with a third opening at the same end of the case intermediate said shackle openings, a shackle adapted to engage said shackle openings, a bolt located in said third opening, means for operating said

bolt, and a filler plug for said third opening, which serves as a bolt carrier; substantially as described.

16. In a padlock, a case having a round opening, a filler plug for closing said opening; a sliding bolt engaging a bore in said filler plug, and adapted to extend out of said bore at the edge of the filler plug, means for operating said bolt, and a shackle connected with the case and controlled by said bolt; substantially as described.

In witness whereof, I have hereunto set my hand on the 24th day of August, 1914.

FRANK I. KIMBALL.
